UNITED STATES PATENT OFFICE.

ADE CHAMBERLAIN AND JESSE CHAMBERLAIN, OF WYNOT, NEBRASKA.

RUNNING-GEAR FOR WAGONS.

1,333,463.

Specification of Letters Patent.

Patented Mar. 9, 1920.

Application filed November 27, 1918. Serial No. 264,339.

To all whom it may concern:

Be it known that we, ADE CHAMBERLAIN and JESSE CHAMBERLAIN, citizens of the United States, and residents of Wyo-
5 ne, in the county of Cedar and State of Nebraska, have invented a new and Improved Run-
ning-Gear for Wagons, of which the follow-
ing is a description.

Our invention relates to the circle and
10 hounds of a wagon running gear, and the
general object of the invention is to provide
a construction in which the elements forming
the hounds are returned to a connection
15 with the axle and so positioned as to con-
stitute a pocket for receiving the wagon
tongue.

The stated object and others as will ap-
pear are attained in the manner explained in
the specific description following.

20 Reference is to be had to the accompa-
nying drawings forming a part of this specifi-
cation, it being understood that the draw-
ings are merely illustrative of one example
of the invention.

25 Figure 1 is a plan view of portions of a
wagon running gear embodying our inven-
tion;

Fig. 2 is a longitudinal vertical section
thereof;

30 Fig. 3 is a transverse section.

In carrying out our invention in accord-
ance with the illustrated example, the circle
10 is formed integrally with the hounds 11,
preferably from angle iron, said circle and
35 hounds being equipped with the usual bow
12 secured between its ends to the circle by
eyes 13 on blocks 14, the forward down-
wardly bent ends 12^a of the bow being en-
tered in the hounds 11. Thus, the reach 15
40 extends from the king bolt 16 rearwardly be-
tween the said circle and bow.

In accordance with our invention the ma-
terial constituting the hounds 11 is return-
45 bent at an acute angle from the front ends
of said hounds rearwardly, parallel with
each other as at 17. The said rear ends are
disposed between the axle 19 and bolster 20
and secured by vertical bolts 18 having spac-
50 ing sleeves 21 thereon. The returned mem-
bers 17 are spaced a distance to snugly ac-
commodate the tongue 22 therebetween.
The returned members 17 thus secured to
the axle and integral with the hounds firmly
55 brace the latter and provide at the same time
a convenient pocket for the tongue.

A bolt 23 extends transversely through the
hounds 11 and through the return members

17 and is adapted to pass through the tongue
22, so that the latter may have vertical sway.
Incidentally, the construction gives an effec-
tive leverage of the tongue on the hounds in
turning. Preferably, in practice, strap
60 braces 24 extend from the axle 19 to the
outer sides of the hounds 11, the bolt 23
passing through said braces, and the nuts 25
65 on the opposite ends of the bolt being out-
side of the braces. The numeral 26 indi-
cates the usual vertical bolts securing the
hounds at the axle and bolster.

We would state in conclusion that while
the illustrated example constitutes a practi-
cal embodiment of our invention, we do not
limit ourselves strictly to the mechanical de-
tails herein illustrated, since manifestly the
70 same can be considerably varied without de-
parture from the spirit of the invention as
defined in the appended claims.

Having thus described our invention, we
claim as new, and desire to secure by Let-
ters Patent:

1. In a running gear, a circle, hounds in-
tegral with the circle, and members integral
with the hounds at the front ends and re-
turned rearwardly therefrom to the axle of
the vehicle, and means securing said re-
80 turned members at their ends to the axle,
said returned members being parallel and
spaced to form a pocket to receive the
wagon tongue.

2. In a running gear, the combination 90
with an axle and bolster, of a circle having
forwardly projecting and inwardly inclined
members extending between the bolster and
axle and terminating in rearwardly extend-
ing parallel and spaced members forming 95
with the first member hounds, the said parts
being formed of a single piece of angle iron
and arranged with its horizontal member
at the top, bolts for securing the circle be-
tween the axle and bolster, bolts for securing 100
the ends of the parallel members between
the axle and bolster, and a bow secured to
the circle and having its ends secured to the
inclined members of the circle.

3. In a running gear, a circle having for-
wardly extending and inwardly inclined
members terminating in rearwardly extend-
ing and parallel and spaced members form-
ing with the first members hounds, the whole
being formed from a single piece of angle 105
iron.

ADE CHAMBERLAIN.
JESSE CHAMBERLAIN.
